DEVICE FOR STORING AND BUNDLING
NEWSPAPERS

Gustave D. Dankert, Cary, Ill.

Application March 14, 1951, Serial No. 215,407

4 Claims. (Cl. 100--19)

1

My invention relates to the storing and stacking of papers, such as old newspapers, magazines, circulars and the like, and to the preparation of such material for removal and disposal. It has for its principal object to provide means for ordinary household use by which paper material of the character designated may be accumulated and stored in orderly stacks and such stacks readily compressed and tied into bundles for convenient removal. My invention is particularly adapted for the stacking and bundling of out-dated newspapers which are of substantially uniform size, and it has been described in connection with such material. It is to be understood, however, that the invention is useable in connection with magazines, pamphlets, circulars and other more or less flat papers.

Many households today have a considerable problem in the disposal of various out-dated publications, particularly newspapers, which accumulate very rapidly. These take up considerable room, are heavy and inconvenient to handle in quantities, and frequently constitute a serious fire hazard. At the same time old paper of this nature has currently some technical value and is in demand for various commercial uses so that certain organizations collect it from householders for sale to dealers. In general, it is the object of the present invention to provide simple and easy means for collecting and retaining such paper in stacks, as distinguished from the usual loose and scattered piles, and for quickly and easily tying such stacks into bundles of a size appropriate for expeditious handling by the members of volunteer collection organizations.

Other objects of the invention will be apparent from the following description taken in connection with the drawings which form a part of this specification and in which:

Fig. 1 is a perspective view showing a device constructed in accordance with my invention, partly broken away the better to show the construction thereof.

Fig. 2 is a view similar to Fig. 1, showing my device with the cover member raised and showing a stack of newspapers or the like compressed and tied into a bundle.

Fig. 3 is a view in transverse vertical section taken substantially on the line 3--3 of Fig. 1.

Referring to the drawing, at 10 is shown generally the stacking or bundling device of my invention, having vertically disposed side members 11 and end members 12 which are rigidly secured at their upper ends to a horizontal rectangular frame 13 by any suitable means such as screws

2

14. There are two of the members 11 at each side of the device and two of the members 12 at each end thereof, these being so disposed that each of the members 11 has an outer edge adjacent to an outer edge of one of the members 12 to form a corner member 16 of right angular section at each corner of the device to form a guide frame. The members 11 and 12 are preferably of varying width, being wider at their lower ends than at their upper ends, so that adjacent edges of the members 11 at each side define a space or slot 17 which is wider at its upper end than at its lower end, and the adjacent edges of the members 12 at each end define similar spaces 18. These slots 17 and 18 are closed at their upper ends by the frame 13 and are open at their lower ends as shown.

Each of the angular corner members 16 is provided at its lower end with a horizontally disposed ledge member or abutment 19, which abutments are preferably of dimensions corresponding to the width of the associated members 11 and 12 at the bottom. Each abutment 19 is rigidly secured to its associated vertical members 20 in any suitable way, as by screws 21. These ledge members 19, which constitute supports for the papers to be stacked in the device, are of substantial thickness so as to define horizontal openings or passages 22 and 23, extending from end to end and from side to side of the device respectively, when it is placed upon a floor, table or other horizontal support. It will be noted that in this construction the opening or passage 22 communicates with the slots 18 at the ends of the device and that the passage 23 similarly communicates with the slots 17 at the sides thereof.

In use, the newspapers or similar material to be stacked is placed flat within the device so that the corners are embraced by the angular members 16 and is allowed to fall to the bottom to form a stack 24, resting upon the ledges 19. It will be readily understood that the formation of the stack is guided by the members 16, the inner surface of which are preferably finished 40 smooth so as to prevent sticking and jamming of the paper.

When a sufficient amount of paper has been thus accumulated and stored to form a bundle of a size convenient for handling, means is provided for easily compressing the stack into compact form and tying it into a tight bundle. For this purpose I provide suitable compression members, conveniently in the form of rods 26, which are adapted for placement on the top of the stack, either lengthwise as shown in Fig. 2 or cross-

wise as shown in Fig. 3, with the ends projecting through the slots 18 or 17 as the case may be. The inner edges of the vertical members 11 and 12 are formed with inclined notches 27, which are horizontally aligned, which slope upwardly from the slot openings 17 and 18 and terminate in suitable seats 28 for the members 26.

Thus, with these members in position on the top of the stack, said stack may be readily compressed against the ledge members 19 by pushing down on the compression members 26 with the hand or foot, until the ends of the compression members may be engaged in the aligned notches 27. When the pressure is released the stack will expand slightly so as to hold the members 26 against their seats 28 in the notches. With the stack so retained and compacted it may be readily tied into a bundle by passing twine or other suitable tie 29 around it in both directions, the tie being passed through the openings 17 and 18 and the passages 22 and 23 as clearly shown in Fig. 2. After the bundle has been thus tied, the compression members 26 may be withdrawn endwise from beneath the tie and the bundle then lifted out of the device for disposal.

I preferably provide the device with a suitable top or cover 31 having rigid lugs 32 depending from the lower surface thereof and so spaced as to slidably engage in the angles of the members 16 at their upper ends. When in place, as shown in Fig. 1, the cover 31 acts to stiffen the device and to provide for its auxiliary use as a stool or seat. At the same time the cover is readily removable at any time for the insertion of paper to be stored or for the compression and tying of bundles as above described. I also provide means, such as a clip member 33 of wire or other resilient material secured to the under face of the cover 31 for carrying a ball of twine 34, so that suitable tying material will be available in a convenient and accessible location. The compression members 26 are also carried, when not in use in suitable clips 36 of any convenient construction, which may be arranged on the side members 11 beneath frame 13.

What I claim is:

1. A device for bundling a stack of newspapers or the like comprising a frame including spaced vertical members formed to embrace the corner edges of the stack and defining side and end

slots open at the bottom, stack supporting ledges secured to the lower ends of the members and projecting within the frame, and compression members removably secured to the edges of the vertical members adjacent oppositely disposed slots to retain the stack in position against said ledges while tying said stack through the slots into a bundle.

2. A device for stacking and bundling newspapers and the like comprising a guide frame including spaced, vertically disposed angular corner guides for the paper to be stacked, said guides being formed with horizontally aligned, upwardly sloping notches, ledge members secured to the lower ends of the guides within the angle thereof to support the lower corners of the stack, and compression rods removably engageable in said pairs of notches transversely to engage the top of the stack.

3. A device for stacking and bundling newspapers and the like comprising a guide frame including angular guide members rigidly connected to embrace the corners of and align the sheets to be stacked, said members being spaced to define openings at the sides and ends of the frame and being formed at the edges of said openings with aligned notches, stack supporting members secured to the lower ends of the guide members and disposed within the frame to support the stack, and compression members for said stack removably engageable in said notches to retain the stack for tying into a bundle.

4. A device for stacking and bundling newspapers and the like comprising a guide frame including vertically disposed members arranged in pairs to form angular corner guides for the paper to be stacked and horizontally disposed members rigidly connecting the upper ends of said vertical members, said vertical members being formed with oppositely disposed aligned notches, a ledge member secured to the lower end of each said corner guide within the angle thereof to support a lower corner of the stack, compression rods to engage the top of the stack adapted to seat in said notches, and a frame stiffening cover member having spaced depending lugs removably engageable in the angles of said corner guides and adapted to rest on the horizontally disposed members.
